US00D760179S

(12) **United States Design Patent**
Chen et al.

(10) **Patent No.:** **US D760,179 S**
(45) **Date of Patent:** ** *Jun. 28, 2016

(54) **LIGHT-EMITTING DIODE DEVICE**

(71) Applicant: **EPISTAR CORPORATION**, Hsinchu (TW)

(72) Inventors: **Chao Hsing Chen**, Hsinchu (TW); **Tsun Kai Ko**, Hsinchu (TW); **Chien Fu Shen**, Hsinchu (TW); **Jia Kuen Wang**, Hsinchu (TW); **Hung Che Chen**, Hsinchu (TW); **Chun Teng Ko**, Hsinchu (TW); **Chien Chih Liao**, Hsinchu (TW)

(73) Assignee: **EPISTAR CORPORATION**, Hsinchu (TW)

(*) Notice: This patent is subject to a terminal disclaimer.

(**) Term: **14 Years**

(21) Appl. No.: **29/506,940**

(22) Filed: **Oct. 22, 2014**

(57) **CLAIM**

The ornamental design for a light-emitting diode device, as shown and described.

DESCRIPTION

FIG. 1 is a perspective view of a light-emitting diode device showing our first example of the new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of a light-emitting diode device showing our second example of the new design;

FIG. 10 is another perspective view thereof;

FIG. 11 is a front elevational view thereof;

FIG. 12 is a rear elevational view thereof;

FIG. 13 is a left side view thereof;

FIG. 14 is a right side view thereof;

FIG. 15 is a top plan view thereof; and,

FIG. 16 is a bottom plan view thereof.

The broken line showing is for the purpose of illustrating environmental structure only and forms no part of the claimed design.

1 Claim, 12 Drawing Sheets
